US00D866494S

(12) **United States Design Patent** (10) **Patent No.:** **US D866,494 S**
(45) **Date of Patent:** ** *Nov. 12, 2019

(54) **MONITOR**

(71) Applicant: **LG ELECTRONICS INC.**, Seoul
(KR)

(72) Inventors: **Hyeongyeol Kim**, Seoul (KR);
Junghan Ryu, Seoul (KR); **Gangho Woo**, Seoul (KR)

(73) Assignee: **LG Electronics Inc.**, Seoul (KR)

(*) Notice: This patent is subject to a terminal disclaimer.

(**) Term: **15 Years**

(21) Appl. No.: **35/505,092**

(22) Filed: **Dec. 6, 2017**

(80) **Hague Agreement Data**

Int. Filing Date: **Dec. 6, 2017**

Int. Reg. No.: **DM/098941**

Int. Reg. Date: **Dec. 6, 2017**

Int. Reg. Pub. Date: **Jun. 8, 2018**

(30) **Foreign Application Priority Data**

Jun. 7, 2017 (KR) 30-2017-0025610

(51) **LOC (12) Cl.** **14-03**

(52) **U.S. Cl.**

USPC **D14/126**
